UNITED STATES PATENT OFFICE.

WILLIAM ZABEL, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

KEYBOARD FOR PRINTING-TELEGRAPH APPARATUS.

1,137,044.

Specification of Letters Patent. Patented Apr. 27, 1915.

Application filed April 28, 1914. Serial No. 834,981.

To all whom it may concern:

Be it known that I, WILLIAM ZABEL, a citizen of the United States, residing at Edgewood Borough, in the county of Allegheny and State of Pennsylvania, have invented certain new and useful Improvements in Keyboards for Printing-Telegraph Apparatus, of which the following is a specification.

10 My invention relates to keyboards for printing telegraph apparatus.

One object of my invention is the provision of means for preventing the repetition of a signal in case a key is held in 15 the depressed position.

I will describe one form of keyboard embodying my invention, and will then point out the novel features thereof in claims.

The accompanying drawing is a sectional 20 view, partly diagrammatic, showing one form of keyboard embodying my invention.

Referring to the drawing, the keyboard comprises a suitable frame 1 in which a key 2 is pivotally mounted on a rod 3 extending transversely through the frame. It is understood that this key is one of a plurality of similar keys all of which are pivotally mounted on the rod 3. The key 2 is biased to the raised position against a stop 4 by a 25 spring 5, and may be depressed against the action of this spring until it is stopped by a bar 6 fixed in the frame 1.

7, 7, etc., are a plurality of flexible contact fingers each of which is adapted to be moved into engagement with a corresponding fixed contact 7^a, and each of which again moves out of such engaging position, due to its own resilience, when the pressure upon it has been removed. Means are provided 35 for each key whereby the depression of the key closes one or more of these contacts, which means I will now describe. Each contact finger 7 is provided with a rocker arm R, each of which arms is mounted to oscillate on an individual rod 8 mounted in the frame 1, and each of which arms is operatively connected with the corresponding finger 7, by suitable means which is indicated diagrammatically in the drawing. Fixed in 40 each rocker arm is a rod 9 which extends transversely across the frame 1 and by means of which the arms may be rocked. The rear end of each key 2 is upturned and

terminates in proximity to a bar 10 mounted to reciprocate in the frame 1, each key 55 being provided with a similar bar. Each bar 10 is provided with one or more lips 10^a which project into the path of one or more of the rods 9, so that these lips serve to move one or more of the rocker arms R when the 60 bar 10 is moved forward, thereby closing the corresponding contact finger or fingers 7. Each bar 10 is provided with a different combination of lips 10^a, so that each key 65 closes a different combination of contacts. It is understood that each rocker arm R is biased to the position shown by the resilience of its contact finger 7, so that when key 2 returns to its elevated position the bar 10 is returned to the position shown by 70 the action of the rocker arms R on the lips 10^a.

S is a sunflower which is controlled by key 2 and which coacts with the contacts 7—7^a in the usual and well known manner 75 to transmit signals over a telegraph line L. This sunflower comprises a fixed annular block 12 of insulation in which are mounted eight contact disks 13. 11 is a shaft which is continuously rotating in the direction of 80 the arrow, and on which an arm 14 is frictionally mounted. This arm 14 carries a contact finger 15 which sweeps over the contact disks 13 when the arm is rotated by the shaft 11.

Owing to the friction between shaft 11 and arm 14, the normal tendency is for the arm to rotate with the shaft, but this rotation of the arm is prevented, except when desired, by a pawl 16 pivotally mounted at 90 16^b in the frame 1 and biased by a spring 16^a to operative position in the path of arm 14. The pawl 16 may be swung out of operative position by a stem 17 which is actuated by a hammer 18 when the key 2 is struck, the 95 mechanism between the key and the hammer being as follows: The hammer 18 is fixed to one end of a resilient bar 19, the other end of which is fixed in an arm 24 which latter is rigidly clamped to a shaft 23 suitably 100 mounted to oscillate in the frame 1. Also rigidly fixed to shaft 23 is an arm 22 which carries a universal bar 21 extending across the keyboard under all of the keys 2. The vertical movements of bar 21, and consequently the oscillations of shaft 23, are re-

- stricted by a stop 26 fixed to the frame 1 and having a jaw in which the bar 21 moves. The bar 21 is biased to the raised position by a spring 25.
- 5 When the key 2 is depressed it strikes bar 21 as it approaches stop 6, thereby swinging hammer 18 upwardly. The parts are so adjusted that when the key is in its depressed position against stop 6, hammer 18 is a short distance below the lower end of stem 17 and the arm 14 is therefore not then released. When however key 2 is suddenly depressed, hammer 18 is swung upwardly, and the inertia of the hammer is such that it bends the 15 bar 19 and continues its upward movement, striking stem 17 a sudden blow and thereby actuating pawl 16; the hammer then immediately retracts from the stem, due to the resilience of bar 19, so that even if the key 20 2 is held down, pawl 16 immediately returns to the operative position. The momentary operation of pawl 16, however, releases arm 14 and allows it to make one revolution, at the end of which it is again stopped by the 25 pawl. During this revolution a signal is transmitted over a telegraph line L, which signal comprises a combination of electrical impulses from a battery 27 depending on which contacts 7'-7" are closed by bar 10.
- 30 It will be seen that if key 2 is held in the depressed position, the signal corresponding to this key is not repeated because the arm 14 makes only one revolution.

Although I have herein shown and described only one form of keyboard embodying my invention, it is understood that various changes and modifications may be made therein within the scope of the appended claims without departing from the spirit 40 and scope of my invention.

Having thus described my invention, what I claim is:

1. A keyboard for printing telegraph apparatus, comprising a key, a continuously 45 rotating shaft, a device to be intermittently rotated and tending to rotate with said shaft, holding means for preventing rotation of said device, a hammer, means controlled by said hammer for releasing said holding 50 means, yielding means interposed between the hammer and the key for moving said hammer when the key is depressed, said hammer being normally out of releasing position when the key is in the depressed position and said hammer having sufficient in-

ertia to carry it momentarily into releasing position when the key is struck.

2. A keyboard for printing telegraph apparatus, comprising a key, a continuously rotating shaft, a device to be intermittently rotated and tending to rotate with said shaft, a pawl for preventing rotation of said device, a hammer adapted to actuate said pawl to release said device, yielding means interposed between the hammer and the key 60 for moving the hammer when the key is depressed, said hammer being normally out of actuating position when the key is in the depressed position, and said hammer having sufficient inertia to carry it momentarily 65 into the releasing position when the key is struck.

3. A keyboard for printing telegraph apparatus, comprising a key, a continuously rotating shaft, a device to be intermittently rotated and tending to rotate with said shaft, holding means for preventing rotation of said device, a resilient bar, means for swinging said bar when the key is depressed, a hammer fixed to said bar, means controlled 70 by said hammer for releasing said holding means, said hammer being normally out of releasing position when the key is in the depressed position, and said hammer having sufficient inertia to carry it momentarily 75 into the releasing position when the key is struck.

4. A keyboard for printing telegraph apparatus, comprising a key, a continuously rotating shaft, a sunflower having an element to be intermittently rotated and tending to rotate with said shaft, means controlled by said key and by said sunflower for signaling, holding means for preventing rotation of said sunflower element, a hammer 90 for releasing said holding means, yielding means interposed between the hammer and the key for moving the hammer when the key is depressed, said hammer being normally out of releasing position when the key 95 is in the depressed position, and said hammer having sufficient inertia to carry it momentarily into releasing position when the key is struck.

In testimony whereof I affix my signature 105 in presence of two witnesses.

WILLIAM ZABEL.
